FLOWER PLANTER

Arthur F. Klingberg, Chicago, Ill.

Application January 24, 1955, Serial No. 34,148

Term of patent 3½ years

(Cl. D35—3)

To all whom it may concern:

Be it known that I, Arthur F. Klingberg, a citizen of the United States, and a resident of the city of Chicago, county of Cook, State of Illinois, have invented a new, original, and ornamental Design for a Flower Planter, of which the following is a specification, reference being had to the accompanying drawing, forming a part thereof in which:

The figure is a perspective view of a flower planter showing my new design.

I claim:

The ornamental design for a flower planter substantially as shown.
